CLAIM

The ornamental design for a portion of a fuse holder, as shown and described.

DESCRIPTION

This application is co-pending application Ser. No. 11/452, 456, filed Jun. 14, 2006, and titled “In-Line Fuse Holder for Female Fuse” to Jacek Korczynski.

FIG. 1 is a perspective view of a portion of a fuse holder showing my new design;

FIG. 2 is another perspective view thereof;

FIG. 3 is a left side view thereof;

FIG. 4 is a bottom view thereof;

FIG. 5 is a perspective view thereof with the fuse cap shown open;

FIG. 6 is a perspective view thereof with the fuse cover removed;

FIG. 7 is a front view thereof with the fuse cover removed;

FIG. 8 is a rear view thereof with the fuse cover removed;

FIG. 9 is a side view thereof with the fuse cover removed;

FIG. 10 is a top view thereof with the fuse cover removed; and,

FIG. 11 is a bottom view thereof with the fuse cover removed.

The broken lines are environmental and form no part of the claimed design.
